Page 2 of 2

Fig. 5.

Fig. 6.

FIG. 1 is a front elevational view of an engine analyzer with timing light showing my new design;

FIG. 2 is a right side elevational view;

FIG. 3 is a bottom plan view;

FIG. 4 is a top plan view;

FIG. 5 is a left side elevational view; and

FIG. 6 is a rear elevational view.

I claim:

The ornamental design for a combined engine analyzer and timing light, substantially as shown.
